(57) **CLAIM**

The ornamental design for an axis ring with brush, as shown and described.

DESCRIPTION

FIG. 1 is a perspective view of an axis ring with brush my new design, the axis ring including blocking member in the form of a brush having a plurality of bristles.

FIG. 2 is an inner side view thereof.

FIG. 3 is an outer side view thereof.

FIG. 4 is a left side view thereof.

FIG. 5 is a right side view thereof.

FIG. 6 is a top view thereof; and,

FIG. 7 is a bottom view thereof.

The broken lines shown are included for the purpose of illustrating portions of the axis ring with brush that form no part of the claim.

1 Claim, 4 Drawing Sheets
